HAND BRAKE

Stacy B. Haseltine, La Grange, Ill., assignor to
W. H. Miner, Inc., Chicago, Ill., a corporation
of Delaware

Application January 25, 1946, Serial No. 643,358

3 Claims. (Cl. 188—81.1)

1

This invention relates to improvements in hand brakes for railway cars, and more particularly to such brakes of the power multiplying type.

One object of the invention is to provide in a hand brake mechanism of the character indicated, including a chain winding drum, a gear rotatable with the drum, a driving pinion meshing with the gear, a driving shaft on which the pinion is fixedly mounted, a ratchet wheel fixed to the driving shaft, and a pivoted locking dog cooperating with the ratchet wheel, simple, efficient and reliable, manually controlled means for positively engaging the dog with and disengaging the same from the ratchet wheel, comprising a lever actuated, rotary trip member which is supported for rotation about the axis of rotation of the driving shaft.

A more specific object of the invention is to provide a hand brake mechanism as set forth in the preceding paragraph wherein the lever operated trip member and dog have cooperating engaging means thereon for positively moving the dog into and out of engagement with the ratchet wheel, and the weight of the lever holds the dog either in operative engagement with the ratchet wheel or disengaged therefrom.

Other objects of the invention will more clearly appear from the description and claims hereinafter following.

In the drawings forming a part of this specification, Figure 1 is a front elevational view of the upper portion of a gear driven, power multiplying hand brake mechanism, illustrating my improvements in connection therewith, the usual hand wheel shaft being shown in vertical section. Figure 2 is a horizontal sectional view, corresponding substantially to the line 2—2 of Figure 1. Figure 3 is a vertical sectional view, corresponding substantially to the line 3—3 of Figure 2. Figure 4 is a fragmentary view, similar to Figure 1, with the front wall of the housing broken partly away, illustrating the parts in a different position. Figure 5 is a broken, front elevational view of the housing, showing the bearing member for the driving shaft and rotary trip element. Figure 6 is a view, similar to Figure 1, illustrating another embodiment of the invention. Figure 7 is a horizontal sectional view, corresponding substantially to the line 7—7 of Figure 6. Figure 8 is a view, similar to Figure 6, showing the upper portion of the housing in vertical section, and the parts of the mechanism in a different operative position. Figure 9 is a view, similar to Figure 6, showing the housing structure only.

2

In the drawings, my improvements are illustrated in connection with a well-known type of gear driven, power multiplying hand brake mechanism, in which the usual brake chain is wound on a brake drum, not shown, rotatable with a relatively large gear 19, driven by a pinion 11, fixed to a shaft 12, which is actuated in a well-known manner by the usual hand wheel, not shown, the hub of which is illustrated and indicated by 13. As is common practice, the operating parts of the hand brake mechanism are enclosed in a housing 14, the upper portion only of which is shown in the drawings.

Referring first to the embodiment of the invention illustrated in Figures 1 to 5 inclusive, my improvements comprise broadly a ratchet wheel A rotatable with the pinion 11; a pivoted locking dog B; a trip element C; and an operating lever D formed integral with the trip element for actuating the latter.

The ratchet wheel A and the locking dog B are contained within an upstanding chamber portion 15 of the housing 14 and the trip element C and operating lever D are mounted exteriorly of the housing.

The locking dog B which cooperates with the ratchet wheel A is pivotally supported above the ratchet wheel on a pivot pin or shaft 16 which extends through an opening 17 at the inner end of the dog. The pivot pin or shaft 16 is arranged horizontally in parallelism with the axis of rotation of the ratchet wheel and has its opposite ends fixed in an inwardly projecting boss 18 on the front wall 19 of the portion 15 of the housing, and an inwardly projecting boss 20 on the rear wall 21 of the housing, which rear wall is in the form of a detachable closure plate. At the outer end thereof, that is, the end opposite to the pivoted end, the dog B is provided with a tooth 22, cooperating with the teeth of the ratchet wheel A. Between its ends, at the lower side thereof, the dog B is provided with a laterally projecting lug 23 of oval transverse cross section, which extends through an arcuate slot 24 in the front wall 19 of the housing and projects some distance outwardly beyond said wall.

The operating shaft 12 which carries the pinion 11 and the ratchet wheel A extends through the front wall 19 of the housing and has its rear end journaled in a bearing boss 25 projecting inwardly from the wall 21 of said housing. The front end portion of said shaft is journaled in inwardly and outwardly projecting bearing bosses 26 and 27 on said front wall, the boss 27 being in the form of a tubular sleeve presenting a cylindrical exterior

bearing surface. At the outer end thereof, the tubular boss 27 is provided with a relatively wide, radially extending lug 128 for a purpose herein-after described. The lug 128 is spaced an appreciable distance outwardly from the front wall of the housing, as clearly shown in Figure 2, thus providing space for mounting the trip element C on the boss 27. As further shown in Figure 2, the shaft 12 extends outwardly beyond the boss 27 to accommodate the usual hand wheel, which is fixed thereto.

The trip element C, which is integral with the operating lever D, is in the form of an annulus journaled on the boss 27, and is of the exterior contour shown most clearly in Figures 1 and 4. The element C has the handle lever D extending radially therefrom and may be rotated to different positions by swinging movement of said lever. Circumferentially spaced shoulders 28 and 29 are provided on the element C which cooperate with the lug 23 of the dog B, the lug 23 being in the path of movement of these shoulders as the lever D is swung from side to side. As shown in Figure 4, the shoulder 29 is located on the element C at the inner end of the lever and, when the lever is swung to the left from the position shown in Figure 4 to the position shown in Figure 1, engages the lug 23 to force the dog B into engagement with the teeth of the ratchet wheel, as shown in Figure 3. Upon reverse swinging movement of the lever back toward the position shown in Figure 4, the shoulder 28 engages the lug 23 and positively lifts the dog out of engagement with the teeth of the ratchet wheel.

To provide for ready application of the element C and its integral handle lever D to the boss 27, the element C is provided with an opening 30 corresponding in shape to the lug 128, but of slightly larger size, so that the lug may pass freely therethrough. In applying the element C and the lever to the boss 27, the lever, together with the element C, is placed so that the opening 30 registers with the lug 128. The element C is then slipped over the boss 27, the lug 128 passing through the opening 30. After the element C has been moved to a position back of the lug 128, the same is held against removal in all possible positions thereof in which the opening 30 does not register with the lug 128. The element C, together with the operating lever D, is thus effectively locked against removal in all operative positions, that is, within the extreme limits of swinging movement of the lever, as shown in Figures 1 and 4.

The operation of my improved hand brake mechanism, shown in Figures 1 to 5 inclusive, is as follows: In applying the brakes, the ratchet wheel is rotated in clockwise direction, as viewed in Figure 1, the dog B ratcheting over the teeth of the same, being held in engagement with the teeth by the action of gravity on the dog B and the weight of the lever D, acting through the shoulder 29 of the element C, which shoulder is in engagement with the lug 23. To release the brakes, the lever D is swung to the right until the shoulder 28 of the element C rests against the lug 23 of the dog. Then, upon relieving the pressure on the tooth of the dog by slightly tightening the brakes, that is, rotation of the ratchet wheel in clockwise direction, the weight of the lever D in its overbalanced position automatically disengages the dog from the ratchet wheel, as clearly shown in Figure 4. The dog B may also be forcibly disengaged from the ratchet wheel by manually swinging the lever D to the position shown in Figure 4 without slight tightening of the

brakes. To reengage the dog with the ratchet wheel, the lever D is swung from the position shown in Figure 4 to the left, to the position shown in Figure 1, thereby engaging the shoulder 29 of the trip element C with the lug 23 of the dog, forcing the latter to swing downwardly into engagement with the teeth of the ratchet wheel.

Referring next to the embodiment of the invention illustrated in Figures 6, 7, 8, and 9, my improvements comprise broadly a ratchet wheel E; a locking dog F; a trip element G; and an operating handle lever H formed integral with the trip element for actuating the latter.

The ratchet wheel E is in all respects similar to the ratchet wheel A hereinbefore described and is mounted in the same manner, being fixed to the driving shaft 12 which also carries the pinion which meshes with the gear through which the brake drum is driven. The front end portion of the shaft 12 extends through the front wall of the housing, being journaled in a tubular boss 31, projecting from said front wall 19. The boss 31 presents a cylindrical, exterior bearing surface on which the element G is rotatably mounted.

The locking dog F is pivotally supported above the ratchet wheel E by a pivot pin or shaft 32 which extends through an opening 33 in said dog. The dog has a tooth 34 at its outer end cooperating with the teeth of the ratchet wheel in the usual manner. On the forward side thereof, the dog is provided with a U-shaped, yokelike portion 35 which is formed integral therewith and presents a pair of depending spaced fingers or arms 36 and 37 for a purpose hereinafter pointed out.

The trip element G is rotatably journaled on the boss 31, being held in place by the hand wheel, not shown, the hub 13 of which is fixed to the shaft 12. The element G is actuated by the lever H, which is integral therewith. On the inner side thereof, the trip element G is provided with a laterally projecting cam lug 38 extending through an arcuate slot 39 provided in the front wall of the housing 14. The lug 38 operates between the arms 36 and 37 of the dog F, and when the lever H is thrown to the left, as shown in Figure 6, engages the arm 36 to throw the toothed end of the dog into engagement with the ratchet wheel and hold it yieldingly engaged for ratcheting action. As shown in Figure 8, the lug 38 engages the arm 37 when the lever H is thrown to the right to disengage the dog from the ratchet wheel and hold it thus disengaged. The weight of the lever H may also be utilized to provide for automatic disengagement of the locking dog by swinging the lever H to the right to a position wherein the lug 38 of the trip element rests against the arm 37 and slightly tightening the brake to relieve the pressure on the tooth of the dog, whereupon the weight of the lever acts to lift the dog out of engagement with the ratchet wheel.

I claim:

1. In a hand brake mechanism, the combination with a member adapted to be rotated to tighten the brakes; of a ratchet wheel rotatable with said member; a pivoted locking dog element engageable with said ratchet wheel; a lug on said dog eccentric to the pivot thereof; a rotary trip element journaled for rotation about the axis of rotation of said ratchet wheel; a radial lever arm on said trip element, said lever arm being engageable with said lug to force the dog into engagement with said ratchet wheel when the lever is swung in one direction and a radial lug on said trip element engageable with said lug

for throwing the dog out of engagement with the ratchet wheel when the lever is swung in a reverse direction.

2. In a hand brake mechanism, the combination with a member adapted to be rotated to tighten the brakes; of a ratchet wheel rotatable with said member; a locking dog pivoted at its inner end and having a tooth at its outer end engageable with said ratchet wheel; a lug on said dog between the pivoted and toothed ends thereof; a rotary trip element mounted for swinging movement about the axis of rotation of the ratchet wheel; a radial operating lever on said trip element, said trip element having a shoulder spaced from said operating lever, said lever and shoulder being respectively engageable with opposite sides of said lug to engage the dog with the ratchet wheel and disengage the same therefrom.

3. In a hand brake mechanism, the combination with a housing having front and rear walls; of a rotary operating shaft rotatably supported by bearing means, said bearing means including an outwardly projecting, tubular bearing boss on said front wall within which said shaft is rotatably supported, said boss having an exterior cylindrical bearing surface; a member rotatable with said shaft for tightening the brakes; a ratchet wheel fixed to said shaft; a dog pivotally mounted above said ratchet wheel, said dog hav-
